SUNSHADE.

No. 19,635.

Patented Feb. 4, 1890.

UNITED STATES PATENT OFFICE.

CHARLES FALCIMAIGNE, OF PARIS, FRANCE.

DESIGN FOR A SUNSHADE.

SPECIFICATION forming part of Design No. 19,635, dated February 4, 1890.

Application filed September 12, 1889. Serial No. 323,778. Term of patent 7 years. Patented in France May 21, 1889, No. 13,425.

To all whom it may concern:

Be it known that I, CHARLES FALCIMAIGNE, umbrella and sunshade manufacturer, a citizen of the Republic of France, at present residing at 91 Boulevard Sébastopol, in Paris, 5 Department of Seine, France, have invented and produced a new and original Design for Sunshades, (for which I have obtained Letters Patent in France, dated May 21, 1889, No. 13,425,) of which the following is a specification, reference being had to the accompanying photograph, forming part thereof.

The leading features of my design consist in the ornamental surface A just above the 15 cover B, and in the ornamental handle C and tip D at the opposite end, that portion E of the stick between the parts A and C contrasting therewith.

Having thus described my invention, what I claim, and desire to secure by Letters Patent, is—

The design for a sunshade herein-described, and illustrated in the accompanying photograph.

The foregoing specification of my new and original design for sunshades signed by me this 3d day of July, 1889.

CHARLES FALCIMAIGNE.
